UNITED STATES PATENT OFFICE.

GEORGE L. REECE, OF DERBY LINE, VERMONT, ASSIGNOR TO FRED D. BUTTERFIELD AND H. STEWART HASKELL, OF SAME PLACE.

SCREW-PLATE.

SPECIFICATION forming part of Letters Patent No. 320,693, dated June 23, 1885.

Application filed December 31, 1884. (No model.)

To all whom it may concern:

Be it known that I, GEORGE L. REECE, a citizen of the Dominion of Canada, residing at Derby Line, in the county of Orleans and 5 State of Vermont, have invented certain new and useful Improvements in Screw-Plates, of which the following is a specification, reference being had therein to the accompanying drawings.

10 My invention relates to that class of screw-plates in which a hub or collet for holding the divided die is interposed between the die and the stock.

The object of my invention is to provide a 15 screw-plate in which the divided die shall be held in position in such a manner as to prevent any motion of the same in relation to the collet when in operation, and also to prevent any motion of one part of the die in 20 relation to the other, thereby preventing "cocking" or tilting of the die and the production of an imperfect screw-thread—in short, to make of an adjustable die a solid die for the time being.

25 In the accompanying drawings, in the various figures of which the same letters designate like parts, Figure 1 is a side elevation of the complete collet, consisting of the body *a* and the cap *b*. Both are threaded and screwed 30 together. Fig. 2 is a vertical section of the collet with the die in place, and showing in detail the construction of the several parts. Fig. 3 shows the guide side of the collet with the guide-jaws *d d d d* and the chipways *e e e e*. Fig. 4 is a top plan view of the collet with the cap *b* in place, and shows through 35 the opening in the cap the cutting-jaws of the die *c c'*. Fig. 5 is a top plan view of the body of the collet with the cap removed, and 40 showing the divided die *c c'* in position.

The screws *f f* (shown in Figs. 1, 2, and 5,) serve the purpose of adjusting the parts of the die relative to each other and to the guide jaws *d d d d*. Adjustment is ordinarily 45 required only to compensate for wear of the die and corresponding tap. The heads of the screws, when the die is adjusted, do not project from the collet, which is designed to enter a circular opening in the stock, where it 50 is held by a pointed set-screw entering the conical depression *h* in the body of the collet. Another conical depression is made in cap at

i, whereby an easy and expeditious method of attaching to and separating the cap from the body is obtained in the manner following: 55 The pointed set-screw, heretofore mentioned, is made to engage with the cap instead of the body, and the insertion of a piece of iron of oblong section (held in a vise) into the space *e*, Fig. 3, gives resistance to the revolution of 60 the body, when by a rotary movement of the stock the cap is unscrewed or screwed on. The cap *b*, when in position, is screwed down upon the die, covering nearly its entire surface, and holds it solidly within the chambered 65 collet, the die resting upon the bottom or floor of the chamber. It will be understood that the office of the cap is to prevent the tilting of one or both parts of the die, in addition to its apparent function of preventing the die 70 from falling out or moving in a line with the axis of the collet.

I am aware that solid dies are commonly held in position by a cover variously attached to the stock, and I do not claim the cap for 75 this purpose; but its office, as indicated, is to keep each part of the divided die in exactly the same plane with the other part.

An advantage over some screw-plates now in use is that as the die is set in the body of 80 the collet, instead of in the cap, the chipways in the die and collet always coincide, forming clear passages in a straight line.

It will be observed that the die used is rectangular in outward form and fits closely a 85 rectangular chamber in the collet, whereby the die is held more firmly and solidly than is possible with a circular die in a circular chamber.

Having thus fully described my invention, 90 I claim as new and desire to secure by Letters Patent—

The combination, with the circular collet having the guiding-jaws *d d* and the rectangular recess for containing the die, of the 95 cap or cover *b*, screwed upon the collet and retaining the die within the recess, substantially as described.

In testimony whereof I affix my signature in presence of two witnesses.

GEO. L. REECE.
